SELF-CONTAINED BOOSTER CYLINDER

Olga Hramoff, Bronx, N.Y.

Application July 6, 1956, Serial No. 596,283

3 Claims. (Cl. 60—54.5)

My invention relates to a new and useful improvement in the technique for boosting or increasing the pressure of a fluid medium. More precisely, this device takes a relatively low input air or hydraulic pressure, magnifies it manifold, and delivers this high output force to a working piston which is part of the original device.

The principal object of my invention is to provide a double acting cylinder capable of a low force approach stroke and a short, high pressure stroke, the high pressure stroke being many times greater than the product of input pressure and cylinder cross-sectional area.

A further object of my invention is to provide a cylinder as described above which will be less expensive to build and operate than a complete hydraulic system or an air operated booster system delivering the same output force at the same rates.

My invention consists of the novel parts in the combination and arrangement thereof, which are defined in the appended claims, and of which three embodiments are exemplified in the accompanying drawings, which are hereinafter particularly described and explained.

Throughout the description primed reference numbers are applied to the same member or to similar members of the different embodiments.

Figure 1 is a side elevation, partly in section, of the first embodiment, showing the pistons in their top-most position. This figure completely describes one variation of this invention.

Figure 2 is a side elevation, partly in section, of the second embodiment, showing the pistons in their top-most position. This figure completely describes a second variation of this invention. Figure 3 is a side elevation, partly in section, of the third embodiment, showing the pistons in their top-most position. This figure completely describes a third variation of this invention.

Referring to Figure 1, it is seen that the upper section of the cylinder contains piston 1 fastened to rod 2, the assembly supported by spring 3. Rod 2 contains continuous oil passage 4, 5 and 6, which, in the position shown, connects the upper oil chamber A with the lower oil chamber B via oil channels 7 and 8. Piston 9 is free to move along rod 2 and is supported in the position shown by the oil in chamber A. The lower section of the assembly contains piston 10 firmly connected to rod 11. Chambers A and B and passages 4, 5, 6, 7 and 8 are filled with oil via port 12.

With the device in the position shown, air under pressure enters through port 13 and forces piston 9 to move down, transmitting pressure via the oil in chamber A and passages 4, 5, 6, 7 and 8 to chamber B and piston 10 forcing it to move down at the same rate as piston 9. Piston 1 remains stationary since the force exerted against it is not sufficient to compress spring 3. Pistons 9 and 10, therefore, descend until rod 11 encounters resistance 14. The back pressure now created allows the air entering port 13 to compress and build up pressure in chamber A sufficient enough to overcome the

2

resistance of spring 3 and force piston 1 to move down. The downward motion of piston 1 will force air from chamber C via passage 15 and misalign passages 6 and 7 prohibiting the transmission of pressure from chamber

5 A to chamber B via the oil passages 4, 5, 6, 7 and 8. The entire force developed by the air acting against pistons 9 and 1 will now be concentrated in area 16, creating a large increase in pressure in chamber B. The resulting force acting against resistance 14 will be seen

10 to be equal to

$$\frac{D^4}{d^2} \times p \times (FF) \times \frac{\pi}{4}$$

where;

D=inside diameter of cylinder

d=diameter of rod 2

FF=friction and area factor

p=inlet air pressure

Applying air pressure to port 17 will raise the pistons back to the position shown in Figure 1.

20 Figure 2 is similar to the embodiment shown in Figure 1 with the exception that a common piston rod is used so that more accurate guidance of any load fastened to the piston rod may be achieved.

25 Referring to Figure 2, it is seen that piston 1' is now permanently fastened to tube 18, the assembly being supported by spring 3'. Oil passages 19, 20, 21, 7' and 8' now connect oil chambers A' and B'. Air pressure entering the top of the cylinder at 13' forces piston 9' to displace oil from chamber A' to B' via passages 19,

30 20, 21, 7' and 8', creating pressure on piston 10' which moves rod 22 down. Rod 22 moves down until encountering resistance 14'. Pressure now builds up in chamber A' sufficient to overcome the resistance of spring

35 3', thus allowing piston 1' and tube 18 to move down. Bushing 23 is part of tube 18 and moves with it. Tube 18 moves down forcing bushing 23 ahead of it and at the same time creates a misalignment between oil channels 21 and 7', shutting off the flow of oil between

40 chambers A' and B'. Further displacement of piston 1' down carries tube 18 and bushing 23 with it and increases the oil pressure in chamber B' over chamber A' by a factor approximately equal to

$$\frac{D^2}{d^2 - d'^2}$$

45 This increased pressure acts against piston 10' to greatly increase the force working against resistance 14'. Releasing the air pressure at port 13' will allow spring 3' to relax and return channel 21 to alignment with channel 7'. Air pressure entering port 17' will return the internal assembly to the position shown in Figure 2.

50 The embodiment illustrated in Figure 3 is identical to the device seen in Figure 1 with the exception that it is completely hydraulic and requires no initial oil fills. The 55 output forces realizable with this device are greater by the ratio of input pressure than those realizable with the air-oil cylinder.

The major difference between the embodiment of Figure 3 and Figure 1 is that in Figure 3 piston 9 is omitted and oil entering port 13'' flows to chamber B'' via central oil channels 24, 6', 7'' and 8''. Chamber C'' contains air which is forced out through port 15'' when piston 1'' moves down.

65 All three variations of this invention have a relatively low pressure upstroke and can create high pressure only after encountering resistance anywhere along the downstroke. These devices do not in any way depend on gravity and can, therefore, be operated at any angle. Although not herein shown, the guide rod technique used 70 with the pneumatic cylinder of Figure 2 can be employed in the hydraulic variation of Figure 3.

This completes the description of the illustrated embodiments. However, I wish it to be understood that my invention is not to be limited to the specific form or arrangement of parts herein described and shown.

I claim:

1. A self contained booster cylinder assembly comprising two chambers separated by a stationary disc and central bushing, said bushing being centered within the stationary disc and containing passageways to allow the flow of hydraulic fluid, a first chamber containing a first piston fastened to a piston rod, one end of said piston rod being guided by the bushing centered within said stationary disc and the other end of said first piston rod guiding a third piston which is in turn guided by the walls of the first chamber and is free to move relative to said piston rod, a compression spring which wraps around said first piston rod and part of said central bushing and is located between said first piston and said stationary disc, the space between said first and third pistons containing an incompressible hydraulic fluid, passages in said first piston rod which in its initial or starting position are in exact alignment with said passages in said central bushing and which when external air pressure is brought to bear upon said third piston, allows the free flow of said hydraulic fluid from said fluid containing space in said first chamber to said second chamber, a second piston and piston rod fastened to it in said second chamber which then moves under the influence of said hydraulic fluid, said second piston being the work piston, cooperating means existing between said first piston rod and said central bushing to block said oil passages when said second piston rod encounters resistance to its movement anywhere along its stroke, that means being the misalignment of said hydraulic fluid passages, said misalignment brought about by a relatively small movement of said first piston rod, the length of which is small in distance and is independent of the stroke of said second piston rod, said misalignment occurring after the hydraulic fluid pressure in said first chamber becomes large enough to overcome the resistance of said compression spring, a second end plate closing off the aforementioned second chamber except for a through bearing hole which serves as a guide to the movement of the aforementioned second piston rod, said end plate containing an air passage, said passage connecting the air space formed between the aforementioned second piston and said end plate to either atmosphere if a work stroke is required or, a source of high pressure air if a return stroke is required, a first end plate closing off the aforementioned first chamber and forming a first air containing space between itself and the aforementioned third piston, said first end plate containing an air passage, said air passage connecting said first air containing space to either a source of high pressure air if a work stroke is required or, atmosphere if a return stroke is required, and upon misalignment of said hydraulic fluid passages, presuming a work stroke is in progress, further movement of said second piston rod against its encountered resistance comes as a result of pressure applied to said hydraulic fluid in said second chamber by said first piston rod, bringing about a multiplication of specific hydraulic fluid pressure in said second chamber in the ratio of said second piston area to said first piston rod area, whereupon after the completion or partial completion of a work stroke it will be necessary to switch said first air passage in said first end plate to atmosphere and introduce air pressure into said second air passage in said second end plate, in order to move the aforementioned first, second and third pistons back to their initial or starting positions.

2. A self contained booster cylinder assembly comprising two chambers separated by a stationary disc and central bushing, said bushing being centered within the stationary disc and containing passageways to allow the

flow of hydraulic fluid, a first chamber containing a first piston fastened to a piston rod, one end of said piston rod being guided by the bushing centered within said stationary disc and the other end of said first piston rod guiding a third piston which is in turn guided by the walls of the first chamber and is free to move relative to said piston rod, a compression spring which wraps around said first piston rod and part of said central bushing and is located between said first piston and said stationary disc, the space between said first and third pistons containing an incompressible hydraulic fluid, said first piston rod containing an axial hole, said axial hole fitted at each end with bearings which serve to guide a second piston rod connected to a second piston, said second piston contained in said second chamber, said second piston rod smaller in diameter than said axial hole in said first piston rod the difference in diameters between said second piston rod and said axial hole in said first piston forming a clearance passage, said clearance passage connecting to passages in said first piston rod, said passages in said first piston rod in its initial or starting position being in exact alignment with said passages in said central bushing and which when external air pressure is brought to bear upon said third piston, allows the free flow of hydraulic fluid from said fluid containing space in said first chamber to said second chamber causing the movement of said second piston, said second piston being the work piston, said second piston rod extending through bearings in a first end plate closing off said first chamber and forming a first air containing space between itself and the aforementioned third piston, said first end plate containing an air passage, said air passage connecting said first air containing space to either a source of high pressure air if a work stroke is required or, atmosphere if a return stroke is required, a second end plate closing off said second chamber and forming a second air containing space between itself and the aforementioned second piston, said second end plate containing an air passage connecting said second air containing space to either atmosphere if a work stroke is required, or a source of high pressure air if a return stroke is required, bearings in each of the first and second end plates providing accurate guidance of said second piston rod, cooperating means existing between said first piston rod and said central bushing to block said oil passages when said second piston rod encounters resistance to its movement anywhere along its stroke, that means being the misalignment of said hydraulic fluid passages, said misalignment brought about by a relatively small movement of said first piston rod, the length of which is small in distance and is independent of the stroke of said second piston rod, said misalignment occurring after the hydraulic fluid pressure in said first chamber becomes large enough to overcome the resistance of said compression spring whereupon, after misalignment of said hydraulic fluid passages presuming a work stroke is in progress, further movement of said second piston rod against its encountered resistance comes as a result of pressure applied to said hydraulic fluid in said second chamber by said first piston rod, bringing about a multiplication of specific hydraulic fluid pressure in said second chamber in the ratio of said second piston area to said first piston rod net area.

3. A self contained booster cylinder assembly comprising two chambers separated by a stationary disc and bushing, said bushing being contained within the stationary disc and containing passageways to allow the flow of hydraulic fluid, a first chamber containing a first piston fastened to a piston rod, one end of said piston rod being guided by the bushing centered within said stationary disc, a compression spring which wraps around said first piston rod and part of said central bushing and is located between said first piston and said stationary disc, a first end plate closing off said first chamber, said end plate containing a passage, said passage connecting

either a source of external hydraulic fluid pressure if a work stroke is required or a hydraulic fluid sink if a return stroke is required, to the space bounded by said end plate and said first piston, said space also containing hydraulic fluid, passages in said first piston rod which, in its initial or starting position are in exact alignment with said passages in said central bushing and thereby allows the flow of hydraulic fluid from an external source through the first fluid containing space to the second chamber, a second piston and piston rod fastened to it in said second chamber which will move under the influence of hydraulic fluid flow into said second chamber, said second piston being the work piston, cooperating means existing between said first piston rod and said central bushing to block said oil passages when said second piston rod encounters resistance to its movement anywhere along its stroke, that means being the misalignment of said hydraulic fluid passages, said misalignment brought about by a relatively small movement of said first piston rod, the length of which is constant and small in distance and is independent of the stroke of said second piston rod, said misalignment occurring after the hydraulic fluid pressure in said first chamber becomes large enough to overcome the resistance of said compression spring, a second end plate closing off the aforementioned second chamber except for a through bearing hole which serves as a guide to the movement of the aforementioned second piston rod, said end plate containing a hydraulic fluid passage, said passage connecting the space formed between said end plate and the aforementioned second piston to either a hydraulic fluid sink if

- 5 a work stroke is required or, a source of hydraulic fluid pressure if a return stroke is required, said space being filled with hydraulic fluid, whereby, after misalignment of said hydraulic fluid passages in said first piston rod and central bushing further movement of said second piston rod against its encountered resistance comes as a result of pressure applied to said hydraulic fluid contained between said second piston and said stationary disc in said second chamber, by said first piston rod, 10 bringing about a multiplication of specific hydraulic fluid pressure in said second chamber in the ratio of said second piston area to said first piston rod area whereupon, after the cylinder has performed a work stroke or part of a work stroke, it will be necessary to externally 15 switch the fluid passage in said first end plate to a hydraulic fluid sink and introduce hydraulic fluid pressure into said second hydraulic fluid passage in said second end plate in order to return the aforementioned first piston and second piston back to their initial or starting 20 position.
